Primary Examiner — Karen S Acker*Assistant Examiner* — Wendy Arminio(74) *Attorney, Agent, or Firm* — Thompson Coburn LLP(57) **CLAIM**

We claim the ornamental design for a misting and sipping bottle cap, as shown and described.

DESCRIPTION

FIG. 1 is a front perspective view taken from the top left corner of the misting and sipping bottle cap showing our new design;

FIG. 2 is a rear perspective view taken from the left bottom rear corner of the misting and sipping bottle cap;

FIG. 3 is a right side view thereof;

FIG. 4 is a left side view thereof;

FIG. 5 is a rear view thereof;

FIG. 6 is a front view thereof;

FIG. 7 is a top plan view thereof; and,

FIG. 8 is a bottom view thereof.

The broken lines in the drawings depict environmental subject matter only and form no part of the claimed design.
